FRANK L. DYER, OF MONTCLAIR, NEW JERSEY

ELECTRICAL REPRODUCING DEVICE

Application filed December 22, 1924. Serial No. 757,488.

My present invention relates to an improved device for securing electrical reproduction from a talking machine record, and particularly from a talking machine record whose record groove is of microscopic size as set forth in my Patent No. 1,570,297, issued Jan. 19, 1926. In securing electrical reproduction from a talking machine record the needle engaging the record groove results in the production of minute telephone currents corresponding to the record, and which may be heard either directly in an ordinary telephone receiver, or be reproduced after suitable amplification by means of a device of the type of a radio loud speaker. When a record groove is of microscopic size as disclosed in said application, with the amplitude of the recorded waves proportionally reduced, it is not possible to secure satisfactory reproduction by direct means such as a diaphragm and horn, because the record is too faint. Therefore some mechanism outside and independent of the record is employed to give the necessary amplification, and the modern vacuum tubes provide ideal means for this purpose since any reasonable degree of amplification can be secured by them with very little distortion. With such a microscopic groove it is important that the needle shall track the groove with very little pressure in order to prevent undue wear, both of the record surface and the needle itself, and even if present forms of devices are employed, the lightness of pressure can be secured by counteracting springs or by suitably balancing the reproducing elements. However I have found in experimenting with extremely microscopic record grooves that it is difficult to have the grooves always in accurate relation to the center of the record, and as a result the needle partakes of a slight movement sidewise back and forth in playing the record. This difficulty may be due to defects in the recording machines or to defects which arise in the process of duplication, or to lost motion between the record and the centering pin on the reproducing machine. Whatever the cause may be, the fact is that I have observed an inevitable tendency of the needle to move from side to side during the playing of the record. With an or-

dinary standard record groove of the order of .005 inch in width, and with a relatively heavy needle engaging such a groove and quickly wearing to entirely fill the same, this movement from side to side is not serious even though the sound box and the parts associated therewith are relatively heavy. But with a very microscopic groove I find that the movement from side to side causes the needle to shoulder very rapidly, and in some cases the needle does not follow the groove throughout its length. It therefore becomes necessary to reduce the inertia of the device as much as possible so as to reduce the detrimental effects due to the movement of the needle from side to side, and to this end I have constructed an improved electrical reproducing device in which the heavier parts are located close to the pivot, permitting the needle to swing across the record in transversing the record groove. In my improved construction the needle and the supports therefore are located at the end of a very light tube, having little inertia so as to minimize the detrimental effects referred to.

Preferably I generate the telephone currents which are to be amplified, by a magnetic or inductive device, rather than by microphone contacts, as in this way the telephone currents will be more free of distortion, and at the same time the telephone construction permits simpler and more effective connection to be made with the needle arm.

In order that my invention may be better understood attention is directed to the accompanying drawings forming part of this specification, and in which:

Fig. 1 is an elevation partly in section showing a turn table carrying a record thereon, and with my improved reproducing device in connection therewith.

Fig. 2 is a section on an enlarged scale of a pivot, and the parts comprising the telephone transmitter showing an arrangement in which the telephone currents are generated by the vibration of a coil in a magnetic field:

Fig. 5 is a side view partly in section on an enlarged scale of the forward end of the supporting tube, the needle arm and the needle:

Fig. 6 a similar view at right angles to Fig. 5:

Fig. 7 a front view of Fig. 5:

Fig. 8 a detail sectional view showing a modified form of telephone transmitter; and

Fig. 9 a corresponding view at right angles to Fig. 8.

In all the above views corresponding parts are represented by the same letters of reference.

In Fig. 1 a turn table 1 is shown carrying a record 2 with which cooperates a needle 3 at the end of a light tube 4 made preferably of aluminum. This tube 4 is secured to a casing 5 which is mounted between pivots 6—6 so as to permit the needle 3 to be moved up and down to accommodate any mechanical variations in the record. This also permits the needle to be changed when desired. The pivots 6 are carried in the ends of a yoke 7 having a stem 8 fitting in the socket 9 and bearing preferably on the ball or pivot 10, whereby the arm 4 may be swung back and forth across the record during the playing of the same. The casing 5 is provided with a complementary part 11 secured to the same by screws 12 and formed with an integral box 13 in which is located a permanent magnet 14 (Figs. 2 and 3) having preferably a central core or leg 15. A very light tube 16 works over the core 15 and between the pole pieces of the magnet and carries a coil 17 in which the telephone currents are generated. These parts in Fig. 3 are somewhat exaggerated. The supporting cylinder 16 in practice should be made extremely thin preferably of bakelite or similar material and the turns of the coil 17 should be very close together. The support 16 is carried by a light arm 18 secured to a resilient strip 19 made preferably of highly tensioned spring steel. This strip 19 is provided at its ends with integral blocks 20, having conical holes therein with which the tapered ends of adjusting screws 21—21 engage. By means of these screws the spring 19 may be placed under the desired tension, and at the same time the position of the strip may be adjusted to accurately position the coil 17 with respect to the poles of the magnet 14. Thus it will be seen that if the lower screw 21 is slightly withdrawn and the corresponding upper screw is slightly advanced, the spring 19 will be adjusted very slightly in an upward direction, Fig. 3. By reversing the operation of these screws the spring will be adjusted in the other direction. Connecting with the spring 19 is a very light hollow rod 22 leading through the tube 4 to the needle arm 23, shown in Figs. 5, 6 and 7. This needle arm 23 is mounted between vertical pivots 24 and is right angular in form, its longitudinal leg

being provided with a suitable recess to receive the needle 3 which is held in place by a clamping screw 25. The lateral leg of the needle arm is secured to the flattened outer end of the tubular rod 22 by means of a screw 25^a as shown in Fig. 6. It will be seen that the spring 19 retains the needle arm and needle in their normal position but at the same time when the needle vibrates, the spring 19 will act like an aperiodic diaphragm and will permit the coil 17 to vibrate in the magnetic field to thereby generate extremely minute telephone currents which are suitably amplified by means of properly arranged vacuum tubes which lead to a suitable radio loud speaker. If the currents are of sufficient magnitude as not to require amplification they may be heard directly in a telephone receiver. In Figs. 8 and 9 a modified form of telephone transmitter is shown in which a magnet 26 is provided with two coils 27—27 working adjacent to the spring 19. With this arrangement the vibration of the spring 19 will generate the currents in the coils 27 which are then suitably amplified. In order to provide for very accurate adjustment of the magnet 26 with respect to the spring 19 I employ two adjusting screws 28—28 engaging conical holes in the magnet as shown in Fig. 8. By loosening upper screw 28 in this figure and tightening the lower screw, the magnet 26 will move to the right whereby reversing the adjustments of these screws it will be moved to the left. It will be understood, that instead of generating the telephone currents inductively, the vibrations of the spring 19 may be made use of to vary the contact between microphone electrodes, in the well known way. It will be seen that the device is one in which most of the mass is located close to the pivot 8 so that inertia is very much reduced, at the same time a very flat construction is presented permitting a relatively shallow cover 29, see Fig. 1, to be used, thus making it possible to house the entire apparatus in a cabinet of small size.

Having now described my invention, what I claim as new therein and desire to secure by Letters Patent is as follows:

1. In an electrical reproducing device the combination of an arm, a needle arm pivoted to the same at one end, a substantially aperiodic flat spring mounted at the other end of the arm, said spring being adapted to maintain the parts in normal position, connections for transmitting vibrations reciprocally between the needle arm and said spring and telephone transmitter mechanism operated by the vibration of the needle arm, substantially as set forth.

2. In an electrical reproducing device the combination of a magnet, a coil influenced by the field of said magnet, a substantially aperiodic flat spring supporting said coil, means

for tensioning said spring, a needle arm and connections to transmit vibrations reciprocally between said needle arm and said spring, substantially as set forth.

5 3. In an electrical reproducing device the combination of a substantially aperiodic flat spring, means at both ends of the spring for tensioning the same, a needle arm, connections for transmitting the vibrations reciprocally between said needle arm and said spring and a telephone transmitting device actuated by the vibrations of said needle arm, substantially as set forth.

10 4. In an electrical reproducing device the combination of a flat spring, means at both ends of the spring for tensioning the same and for simultaneously adjusting the spring bodily, a needle arm, connections for transmitting vibrations reciprocally between the needle arm and said spring and telephone transmitting mechanism actuated by the vibrations of said needle arm, substantially as set forth.

15 This specification signed and witnessed this 17th day of December, 1924.
